UNITED STATES PATENT OFFICE.

JAMES DEAN, OF NEW YORK, N. Y.

INTERNAL-COMBUSTION ENGINE.

1,155,647.

Specification of Letters Patent.

Patented Oct. 5, 1915.

Application filed January 21, 1915. Serial No. 3,464.

To all whom it may concern:

Be it known that I, JAMES DEAN, a citizen of the United States, and resident of New York, in the county and State of New York, have invented certain new and useful Improvements in Internal-Combustion Engines, of which the following is a specification.

This invention relates to internal combustion engines of the two cycle type, and more particularly those engines which are equipped with a pump structure operating in synchronism with the working piston or pistons to clear the burnt gas from and facilitate the ingress of fresh gas to the working cylinder or cylinders.

The object of my invention is to provide an engine of the type mentioned which shall be simple in construction and efficient in operation, the salient feature or features thereof comprising improved valve mechanisms constructed and designed to control, with positiveness and precision, the supply and discharge of gas to and from the engine, as will be hereinafter particularly described and claimed.

In the drawings—Figure 1 is a longitudinal vertical section, partly in elevation, of a two-cylinder engine embodying the preferred form of my invention; the plane of the section being indicated by the line 1—1 of Fig. 4. Fig. 2 is a similar section, as on the irregular line 2—2 of Fig. 5. Fig. 3 is a transverse vertical section, as on the line 3—3 of Fig. 4. Fig. 4 is a transverse horizontal section, as on the line 4—4 of Fig. 3. Fig. 5 is a similar section, as on the line 5—5 of Fig. 3. Fig. 6 is a transverse vertical section of a three-cylinder engine equipped with a modified form of my invention. Fig. 7 is a longitudinal vertical section of the upper portion of the modified structure, as on the line 7—7 of Fig. 6. Fig. 8 is in the main or left hand portion a horizontal section, as on the line 8—8 of Fig. 6; the right hand portion of the figure being broken away to present a section as on the line 8^a—8^a of Fig. 6.

Referring to Figs. 1 to 5, inclusive, of the drawings, 11 designates the working cylinders of which two are illustrated, although, of course, less or more may be employed.

12 designates pump cylinders, larger in diameter than, and constituting, in effect, continuations of, the respective working

cylinders. Fitted to reciprocate in each of the working cylinders and its complementary pump cylinder are the upper and lower heads 13, 14 respectively of a piston 15, the latter head in virtue of its relatively larger diameter effecting a displacement in excess of that of the upper head.

16 designates the crank shaft, and 17 the rods connecting the cranks 18 thereof with the respective pistons, said cranks being in proper angular relation to each other to effect the timely travel of the pistons.

The fuel inlet ports 19 for the respective working cylinders are formed adjacent the top of the latter and are adapted to receive the gaseous mixture directly from the carburetor. An important feature of my invention resides in the mechanism for controlling the periodicity of the inflow of fuel to, and the auxiliary discharge of the burnt gases from the cylinders 11, said mechanism, as will presently appear, including valves, as 20, 20^a, which are concurrently and positively actuated by power transmitted from the main or crank shaft of the engine.

The main exhaust port or ports 21 for each of the working cylinders are formed in the wall of the cylinder near its lower extremity, in order that such port or ports shall be opened only when the correlated working and pump pistons approach the limit of their working stroke.

Each of the piston heads 13 is provided adjacent its periphery with an upstanding ported baffle 22 which is constructed and arranged to open and then close communication between the exhaust ports 21 and the interior of the cylinder 11 as the piston approaches and reaches the limit of its working stroke; that is to say, ports 23 are formed at the foot of the baffle in position to cross the exhaust ports 21 in the down stroke of the piston. Hence, as the piston approaches the extremity of its out or power stroke, the exhaust ports are opened for the discharge of burnt gases from the working cylinder and are then closed.

Two ports 24 connect each of the working cylinders at its foot with ducts 25, 26 leading into the top of the annular chamber comprised between the piston and the pump cylinder, said ports 24 being so located that they are opened immediately after the opening and closing of the exhaust ports 21 by the ported baffle. Consequently the partial vacuum created within the pump chamber

by the down stroke of the piston, withdraws the remaining burnt gases from the working cylinder and induces a flow of fresh fuel into and through the inlet port 19 of the cylinder, such inlet port at that juncture being in open communication with the source of fuel supply. In the upward movement of the piston to compress the charge thus delivered to the working cylinder, the ports 21, 24 are closed by the piston, and concurrently with the initial upward travel of the piston the fuel inlet to the cylinder is positively closed through the agency of the valve 20 above referred to.

15 The duct 26 leads to a duct 27 which periodically communicates with the atmosphere through the rotary valve 20^a which is arranged in spaced relation to and co-axially with the like valve 20 on a vertical shaft 28.

20 The valves 20, 20^a in the form illustrated comprise rotary tubular bodies, headed at their upper ends, and provided in their walls with ports 29, 30 respectively. They are rotatably fitted in a vertical chamber 31 forming a part of the engine wall, the shaft 28 extending axially through such chamber and being geared with the crank shaft to rotate correspondingly therewith. In the present instance the vertical shaft is provided at its lower end with a spiral pinion 32 in mesh with a spur wheel 33 on the crank shaft of the engine.

25 The valve 20 is disposed between two ducts 34 leading to the respective inlet ports 19, and it controls the communication of such ducts with a duct 35 which leads to the bottom of the valve from a carburetor or other source of fuel supply. Thus in each rotation of the crank shaft and the valve 20 the latter is functioned first to open and close communication between the source of fuel supply and one of the working cylinders and then similarly to control the communication between such source of supply and the other working cylinder.

30 The valve chamber 31 communicates at its lower end with a duct 36 leading to the atmosphere and the valve 20^a is adapted in its rotation to open and close communication between said chamber and the exhaust ducts 26.

35 The valve shaft 28 is preferably made in two parts flexibly connected by a two-part coupling head 37 which is fitted to rotate in the space below the valve 20^a and thus prevent communication between such valve and the interior of the crank case. This sectional formation of the valve shaft not only enables the valve mechanism to be easily assembled but it insures the vertical alignment 40 of the two valves and the accurate disposition of the pinion relative to the spur wheel without the otherwise necessity of nice fitting of parts.

45 By the above described construction it will be seen that an engine is provided in which

the use of pressure-controlled valves is avoided, and that, on the other hand, the respective ports are at all times positively controlled; that is to say, the exhaust ports from the working cylinder are directly controlled by the piston and the ported baffle; and the exhaust port from the pump chamber and the inlet port to the working cylinder are controlled by valves operated concurrently, positively and directly from the crank shaft without the interposition of springs, pneumatic chambers or similar agencies. Hence the proper sequential operation of the various ports is positively effected and maintained and in consequence a simple and reliable engine of high efficiency is provided.

50 In Figs. 6, 7 and 8 I have illustrated a three-cylinder engine embodying a modified form of my invention. In this modification the rotary valve for controlling the supply of fuel to the inlet ports 19 of the respective cylinders comprises a cylindrical body 20 having appropriately located ports 29, and having also an axial shaft 28^a mounted to rotate in bearings in a bonnet 39 on the respective working cylinders 11; and the rotary valve for controlling the discharge of the burnt gases from the pump chambers comprises a cylindrical body 20^a having suitably disposed ports 30 and having also an axial shaft 28^b mounted to rotate in bearings in a valve casing on the engine wall. The valve shafts 28^a, 28^b are coupled by suitable gearing so as to rotate concurrently, the lower shaft 28^b being appropriately geared to the crank shaft. In the form illustrated the valve shafts are equipped with sprocket wheels 40, 41 respectively, operatively connected by a chain 42, and the shaft 28^b is also provided with a sprocket wheel 43 which is operatively connected by means of a chain 44 with a similar wheel 45 on the crank shaft.

55 I claim—

1. In an internal combustion engine of the two cycle type, a working cylinder having a fuel inlet port and main and auxiliary exhaust ports in spaced relation to each other, a pump cylinder in communication with the working cylinder through the auxiliary exhaust port, said pump cylinder having a discharge port, a piston adapted to reciprocate within said cylinders and in its travel control the opening and closing of the exhaust ports at predetermined intervals, valve mechanism controlling the fuel inlet port of the working cylinder and the discharge port of the pump cylinder, and gearing between said mechanism and the main shaft of the engine.

2. In an internal combustion engine of the two cycle type, a working cylinder having a fuel inlet port and main and auxiliary exhaust ports in spaced relation to each other, a pump cylinder in communication with the

- working cylinder through the auxiliary port, said pump cylinder having a discharge port, a piston adapted to reciprocate within said cylinders and in its travel control the opening and closing of the exhaust ports at predetermined intervals, a rotary valve for the fuel inlet port of the working cylinder, a rotary valve for the discharge port of the pump cylinder, and gearing between said valves and the main shaft of the engine. 5
3. In an internal combustion engine of the two cycle type, a working cylinder having a fuel inlet port and main and auxiliary exhaust ports in spaced relation to each other, a pump cylinder in communication with the working cylinder through the auxiliary port, said pump cylinder having a discharge port, a piston adapted to reciprocate within said 10 cylinders and in its travel control the opening and closing of the exhaust ports at predetermined intervals, a rotary valve for the fuel inlet port of the working cylinder, a rotary valve for the discharge port of the 15 pump cylinder, a common shaft for said valves, and operative connection between said shaft and the main shaft of the engine. 20
4. In an internal combustion engine of the two cycle type, a working cylinder having a fuel inlet port and main and auxiliary exhaust ports in spaced relation to each other, a pump cylinder forming a continuation of the working cylinder and being in communication therewith through the auxiliary exhaust port, said pump cylinder having a discharge port, a piston adapted to reciprocate within said cylinders, and in its travel control the opening and closing of the exhaust ports at predetermined intervals, a 25 vertically-disposed valve chamber adjacent said cylinders, an axial shaft in said chamber, two rotary valves on said shaft, one for the fuel inlet port of the working cylinder and the other for the discharge port of the pump cylinder, a member on said shaft rotatably mounted within the valve chamber and adapted to close the lower portion of the latter, and gearing between said shaft and the main shaft of the engine. 30
5. In an internal combustion engine of the two cycle type, a plurality of working cylinders having fuel inlet ports at or near the top, and main and auxiliary exhaust ports at or near the bottom, pump cylinders in communication with the respective working cylinders 35 through the auxiliary ports, said pump cylinders having discharge ports, pistons adapted to reciprocate within said cylinders and in their travel control the opening and closing of the exhaust ports of the working cylinders at predetermined intervals, valve mechanism for the fuel inlet ports of the working cylinders, a common rotary valve for the discharge ports of the pump cylinders, and operative connection between said valve and the main shaft of the engine. 40
6. In an internal combustion engine of the two cycle type, a plurality of working cylinders having fuel inlet ports at or near the top thereof and main and auxiliary exhaust ports at or near the bottom, pump cylinders in communication with the respective working cylinders through the auxiliary exhaust ports, said pump cylinders having discharge ports, pistons adapted to reciprocate within said cylinders and in their travel control the opening and closing of the exhaust ports of the working cylinders at predetermined intervals, valve mechanism for the fuel inlet ports of the working cylinders, a common rotary valve for the discharge ports of the pump cylinders, and operative connection between said valve and the main shaft of the engine. 45
7. In an internal combustion engine of the two cycle type, a plurality of working cylinders having fuel inlet ports at or near the top thereof and main and auxiliary exhaust ports at or near the bottom, pump cylinders in communication with the respective working cylinders through the auxiliary ports, said pump cylinders having discharge ports, pistons adapted to reciprocate within said cylinders and in their travel control the opening and closing of the exhaust ports of the working cylinders at predetermined intervals, a common rotary valve for the fuel inlet ports of the working cylinders, a common rotary valve for the discharge ports of the pump cylinders, and operative connection between said valves and the main shaft of the engine. 50
